UNITED STATES PATENT OFFICE.

DAVID BLOCK, OF CHICAGO, ILLINOIS.

KNOCKDOWN TABLE.

1,188,613.

Specification of Letters Patent. Patented June 27, 1916.

Application filed March 28, 1914. Serial No. 827,802.

To all whom it may concern:

Be it known that I, DAVID BLOCK, a citizen of the United States, residing at Chicago, in the county of Cook and State of Illinois, have invented certain new and useful Improvements in Knockdown Tables, of which the following is a specification.

This invention relates to sheet metal tables, and more particularly to tables of this class in which the several parts which constitute the table can be easily and readily dismembered so that the entire table may be encompassed in a small compact space.

A further object of the invention is to provide detachable legs which are releasably locked to the table top.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 is a perspective of a table constructed in accordance with the principles of my invention; Fig. 2 is a detail view of the leg locking device taken on the line 2—2 of Fig. 3; Fig. 3 is a detail view of the leg locking device taken on the line 3—3 of Fig. 2; Fig. 4 is a sectional view showing the shelf fastening taken on the line 4—4 of Fig. 5; Fig. 5 is a sectional view of the same taken on the line 5—5 of Fig. 4; and Fig. 6 is a perspective of one of the spring locking clips.

This invention relates to a collapsible table constructed entirely of sheet metal, which may be closed by removing the legs from engagement with the table and placing them in a recess of the top, the shelf being also of a size to be contained in a recess of the top whereby the entire structure may be closed in a minimum space so that the table will occupy the least space for shipping or storing it away.

Referring more particularly to the drawings, the top comprises sheet metal sides 2 and ends 3 with the edges 4 and 5, respectively, bent inwardly at the lower edge, overlapped and secured together as by means of a rivet 6, the sides and ends being connected in any suitable manner, as for example, by a connection 7 (see Fig. 3) at the junction corners thereof. The surface for the

table top is preferably formed from a single sheet of material 8 with an upwardly extending ridge 9 about the edges which is folded over and secured to the sides and ends 2 and 3 by pressing the folded edges 9 firmly against the sides and ends, or any other suitable manner, leaving a projection 10 on the outside of the sides and ends. This is the preferred construction of the top although, of course, other constructions may be employed. It will be seen that the upper surface is recessed, forming a kind of a pan, and that the top is open from the bottom forming a considerable recess for containing the legs when the table is in knockdown position.

Each leg comprises an angular member 11 formed at the top with hooks 12 which are adapted to engage over the folded edges 9 at the corner where they abut. The extremities of the sides of the angular member 11 are formed with a ridge 12^a, as shown more clearly in Figs. 3 and 4, which terminates below the hooks 12 which is adapted to engage below the projection 10 formed by the folded edges 9 of the top. For a distance from the top of each leg equal to the height of the sides and ends there is no reinforcement other than the ridge 12, as shown more clearly in Fig. 3, but commencing immediately below the side and end is a reinforce 13 the edges of which are clamped in the ridges 12. This reinforce is preferably in two pieces in each leg, ears 14 being bent inwardly therefrom at their junction point which are perforated to form a support for a shelf 15. The extremity of each leg is formed with a bottom bend 16 to form a bearing surface and with a bend 17 at the inner corners thereof which serve to hold the lower reinforce more securely in position and also prevent corners at these points.

In order to lock each leg in connection with the table top a spring clip 18 (see Fig. 6) is provided with the extremities 19 and 20 bent substantially parallel to each other and at an angle to an intermediate portion between them; one extremity 19 being substantially less in length than the other extremity 20. In locking each leg in position the shorter extremity 19 of the locking clip is placed in engagement with the upper edge of the reinforce 13, the hooks 12 are placed in engagement with the bent edges 9 at the junction corner, the leg being inclined outwardly so that the clip 18 is free

from engagement with the bottom of the table top. The leg is then swung inwardly until the ridges 12 engage beneath the projections 10 at the corner, the clip at this time being beneath the bent-in edges 4 and 5 of the side and end 2 and 3 but out of engagement therewith. The clip is then moved into engagement with the bent edges 4 and 5, the extremity 20 of the clip engaging each 10 bent edge at an angle thereto, as shown more clearly in Fig. 3, and the angle of the extremity 20 being such that this extremity must be pressed resiliently over the edges 4 and 5 thereby forcing the table top upwardly so that the hooks 12 engage the upper ridge firmly, the extremities of the ridges 12 engage beneath the projections 10 and the upper edge of the reinforce 13 supports the 15 table top by the engagement of the body of the clip 18 with both the over-lapped turned-in edges 4 and 5 of the side and end members and the upper extremity of the reinforce.

The shelf 15 is preferably formed with 25 bearing edges 21 turned inwardly at the bottom and the corners are cut off at an angle corresponding to the size of the legs so that the shelf will be contained in the space inside of the legs, the shelf being provided with perforations corresponding with 30 the ears 14 through which a fastening device 22 is inserted to hold the shelf firmly in place, thus aiding in reinforcing the table, in properly spacing the legs apart and forming 35 an additional surface or shelf.

In collapsing the table the assembling operations are reversed and the legs are of the size to be contained in the space which opens from the lower side of the top, preferably being of such a length that they must be disposed diagonally therein whereupon they are retained in position by the inwardly bent edges 4 and 5. The shelf 15 being slightly smaller than the table top is 45 adapted to be received in the recessed upper surface.

With this construction the entire table, including the legs, is composed of sheet metal which makes the structure light and 50 strong, the strength being increased in the case of the legs by the reinforce and the strength being added to all the parts by bending the edges thereof. The edges are also bent for the purpose of obviating the 55 sharp cut edges of the metal.

What I claim is:

1. A knock-down sheet metal table comprising a top with sides meeting at an angle, triangular sheet metal legs one side of each terminating short of the other sides to form a support for the top, the other sides of each leg fitting the table closely at the corner, and a spring clip insertible between the under side of the table top and the upper 65 end of the short side of the leg having an

extremity movable to engage the under side of the table top at an angle for holding the leg in connection with the top.

2. A knock-down sheet metal table comprising a sheet metal table top, a removable sheet metal leg having means for engagement with the upper face of the table top and bearing against the side of the table top, and a spring locking clamp engaging the under side of the table and operative to 70 and bearing against the side of the table top and to hold the said means of the leg in engagement with the upper face of the table top for thereby removably attaching each leg separately to the table top.

3. In a sheet metal table, a table top composed entirely of sheet metal with a top surface and depending sides, removable angular legs constructed of sheet metal each having a hook to engage over the top of the 85 table top and disposed adjacent the sides of of the top, and a spring locking clamp to engage both the leg and the under side of the table top to bind the leg releasably against the side of and upper surface of the 90 table top.

4. In combination, a rectangular table top constructed entirely of sheet metal, angular sheet metal legs adapted to embrace the table top at each corner and having a portion adapted to engage the top adjacent the corner, and a spring locking clamp for each leg separate both from the leg and from the top adapted to engage the leg and bind it 95 releasably in engagement with the top. 100

5. A knock-down table comprising a metal top with a ridge thereon, removable legs therefor each having a portion to engage the ridge, and a spring clip for each leg to press the top against the portion of the leg 105 which engages the ridge to hold the leg in position with respect to the top.

6. A knock-down table comprising a sheet metal top with a ridge thereon, removable sheet metal legs with a shouldered portion adapted to engage beneath the ridge, and a removable spring clip locking clamp for each leg to hold the leg against the top and to press the shoulder against and under the ridge.

7. A knock-down table comprising a metal top formed with a ridge, of sheet metal legs therefor each formed with a hook to engage over the ridge and a shouldered portion to engage beneath the ridge, and a spring clip 110 locking clamp for each leg to bind it to the top with the hooked and shouldered portions in engagement with the ridge.

8. A knock-down table comprising a metal top with a projecting ridge, angular metal 115 legs therefor adapted to fit at the corners of the table with hooked extremities to engage over the ridge and with shoulders to engage beneath the projection of the ridge, a reinforcement for each leg extending be- 120 125 130

- neath the table top, and a spring locking clamp for each leg adapted to engage the reinforcement of the leg and the table top beneath the corner thereof.
5. 9. A knock-down sheet metal table comprising a sheet metal top, triangular sheet metal legs having one short side and two sides with hooks at the end to engage over the upper edge of the table top, the short side of each leg extending below the table top, and a spring clip to engage the short side of the leg and the under side of the table top at the corner to hold the hooks in engagement with the upper side of the table and to bind the leg releasably to the table.
10. 10. A knock-down sheet metal table comprising a top with a ridge around the upper edges, triangular sheet metal legs each with one side shorter than the others, the longer sides being formed with hooks at the upper end to engage over the ridge of the top and with shoulders to engage beneath the ridge of the top, and the short side of each leg being adapted to extend beneath the table to form a substantial support therefor, and a spring clip separate both from the leg and from the table top having a bent end insertible between for engaging the upper side of the leg and having another bent end movable to engage the under side of the table top to bind the leg in position.
15. 11. A knock-down metal table comprising a sheet metal top with sides and ends turned inwardly at the bottom thereof, angular sheet metal legs to engage the corners of the table, a reinforcement for each leg, and a spring clip for each leg, one end of which engages the reinforcement and the other end of which is movable to engage the turned-in side and end portion of the top, at the corner thereof for locking the leg releasably in connection therewith.
20. 12. A knock-down table comprising a sheet metal top with an upwardly extending ridge and with the sides and ends turned inwardly at the bottom, of angular sheet metal legs therefor adapted to fit over the corners, each leg being formed with a hook to engage over the ridge of the top and with shoulders to engage beneath the said ridge, a reinforcement for each leg disposed between and extending from a point beneath the turned-in edges of the sides and ends when the legs are
25. 30. in position, and an angular clamp adapted to engage the top of the reinforcement and movable to engage the turned-in side and end at each corner at an angle thereto for locking each leg releasably and independently in position and for binding shouldered and hooked portions in contact with the ridge of the top.
35. 13. A knock-down metal table comprising a rectangular sheet metal top, angular sheet metal legs adapted to engage the top above and below at the corners thereof, a locking clamp to engage each leg and the top for binding it releasably in position with respect thereto, and a member secured to all of the legs for strengthening the structure and holding the lower ends of the legs in position.
40. 14. A knock-down table comprising a rectangular metal top, angular sheet metal legs therefor adapted to engage the top, a reinforcement for each angular leg having a projection inwardly therefrom, a locking clamp for each leg adapted to engage the reinforcement and the under angular corner of the top to hold the leg releasably in position with respect thereto, and a removable shelf adapted to be secured to the inward projections of the leg reinforcements.
45. 15. A knock-down metal table comprising a top with sheet metal sides and ends turned inwardly at the bottom and with a recessed top surface, the sides and ends forming a recess open from the bottom, sheet removable metal legs adapted to engage the top at the corners thereof and of a length to be inserted diagonally within the recess which opens from the bottom of the top for knock-down purposes, a resilient metal clamp for locking each leg in connection with the top, and a shelf adapted to be secured to the legs and to be seated in the depression in the top surface of the table for knock-down purposes.
50. In testimony whereof I have signed my name to this specification, in the presence of two subscribing witnesses, on this 25th day of March A. D. 1914.

DAVID BLOCK.
